UNITED STATES PATENT OFFICE.

JOHN HOHL, OF NEWARK, NEW JERSEY, ASSIGNOR TO MOLDED SOCKET CORPORATION, OF RAILROAD, PENNSYLVANIA, A CORPORATION OF NEW JERSEY.

LAMP SOCKET.

Application filed December 5, 1922. Serial No. 604,993.

This invention relates to lamp sockets of cold moldable insulating material and to a method of making such sockets.

An important object of the invention is to produce a lamp socket having a body entirely formed of cold moldable insulating material, the outside of the body being of the same shape and size as the standard brass shell socket and therefore adapted to receive any standard lamp shade holder.

Another object of the invention is to produce a socket of such insulation having a lamp receiving screw shell molded in place in cold molded material.

Still another object is to provide a quick economical method of making such sockets.

Fig. 1 is a longitudinal section of a female die containing a molded socket.

Fig. 2 is a half section of a socket having a plain insulating collar.

Fig. 3 is a half section of a socket having an insulating thread to receive a shade holder.

Fig. 4 is half section of a socket having a plain metal collar, and

Fig. 5 is a half section of a socket having a threaded metal collar.

My socket may be made of any of the well known cold moldable insulating compounds and in its simplest form consists of a body portion 6 having a tapering shoulder 7 connected by a narrow neck 8 to a collar or band 9, all made in one piece. The neck is of the same external diameter as in the standard brass shell type of socket and is thus adapted to receive any shade holders designed to be secured to the neck portion of standard sockets. The upper edge of collar 9 prevents such shade holders from slipping off. In order that the neck 8 which is necessarily very thin in order to come within the standard dimensions may have sufficient strength to be durable in practical use, I mold a screw shell 10 within the neck portion. The neck portion having considerable inherent strength also reinforces the screw shell, so that I can use a shell of considerably thinner sheet metal than is possible with the usual socket in which the screw shell is not reinforced.

In making my socket I place the screw shell 10 on a suitable collapsible mandrel 11 which is then inserted in one end of a female die 12. I have found it most satisfactory to

employ a one piece die having an upper 55 diameter equal to that of the body portion 6 of the socket, the wall tapering inwardly to form the shoulder 7 and the diameter of the die below the shoulder being equal to that of the collar 9. The die may also be 60 slightly conical as a whole to facilitate withdrawal of the molded articles. After the mandrel and shell are inserted in the die, I put in the required quantity of the insulation and apply pressure as by a male die 65 which may be shaped to produce any desired pockets 13 to hold switch or contact members and an aperture 14 (Fig. 4) for the center contact screw. I next withdraw the mandrel and molded socket from the die. The unbaked socket is easily machined and after coming from the mold I remove a band of material from the outside of the neck portion in order to bring the neck down to standard 70 dimensions and leave the collar 9 with its 75 upper edge which prevents shade holders from slipping out of place. I am able to machine the neck to the required thinness because of the interior support which it receives from the molded in screw shell. If 80 it were not for this support the neck would not be strong enough before the socket was baked to stand machining to the necessary thinness. While the excess neck insulation is being removed, I may also thread the 85 collar portion as at 15 (Fig. 3) to receive standard screw threaded shade holders. After machining, the socket is baked and polished and is then ready for assembly 90 with the contacts.

To render easy the insertion of lamp or plug bases in the screw shell 10, I preferably bevel the lower end of the socket as at 16, thereby producing a sharp edge. If desired this edge may be reinforced by a metal band 95 or collar 17 (Fig. 4) which is molded in during the forming of the socket. In this case the collar fits the lower end of the die and an annular band of insulation must be removed from the molded unbaked socket between the 100 upper edge of the collar and the shoulder portion 7. The collar then provides a metal edge to carry shade holders. The metal band may also be threaded as at 18 (Fig. 5) to receive threaded shade holders.

My invention thus provides a lamp socket which is interchangeable with standard brass sockets, but being made of insulation is less

subject to short circuits or corrosion when in moist or polluted atmosphere. My method of manufacture also permits rapid quantity production at a very low cost.

5 I claim:

1. A socket comprising a molded insulating body having a thin neck integral therewith and a metallic screw shell molded under pressure inside of said thin neck and reinforcing said neck, the outer end of said neck extending beyond said screw shell, said neck having a screw thread integral therewith and projecting therefrom immediately

around a portion of the neck which surrounds a portion of the shell.

15

2. A socket comprising a molded insulating body having a thin neck integral therewith and a metallic screw shell molded under pressure inside of said thin neck and reinforcing said neck, the outer end of said neck extending beyond said screw shell and a screw thread for a shade holder on the outer wall of said neck surrounding a portion of said screw shell.
